UNITED STATES PATENT OFFICE.

JAMES EMERY EATON, OF UTICA, NEW YORK.

IMPROVEMENT IN COMBINED RULERS AND BLOTTERS.

Specification forming part of Letters Patent No. 133,839, dated December 10, 1872.

To all whom it may concern:

Be it known that I, JAMES EMERY EATON, of Utica, in the county of Oneida and State of New York, have invented a new and valuable Improvement in Combined Ruler and Blotter; and I do hereby declare that the following is a full, clear, and exact description of the construction and operation of the same, reference being had to the annexed drawing making a part of this specification, and to the letters and figures of reference marked thereon.

Figure 1 of the drawing is a representation of a bottom view of my invention with the blotting-paper removed. Fig. 2 is a sectional view of the same.

My invention has relation to implements for draftsmen and clerks; and consists in the novel construction and combination of a ruler and attachable plate, adapted for holding a strip of blotting-paper, so arranged that it shall serve as a combined rule and blotter, as hereinafter described.

A of the drawing represents a ruler, usually one foot in length, and graduated by any desirable scale, such as is in common use in offices, schools, &c. B represents an attachable plate, usually of the same length as the rule, and preferably a little less in width. When thus made I advise that the lower edges of the rule be beveled, as shown on the draw-

ing, but such bevel constitutes no essential part of my invention. The letters c c c represent screws which are passed through suitable apertures through both the rule and the plate, securing said rule and plate firmly together, and making the latter removable at will. D represents a strip of blotting-paper passed around the plate B, and held securely in position by being clamped between said plate and rule, and held firmly by means of the screws c.

It is obvious that these blotters can be supplied at will by detaching the plate from the rule. When the plate B is thus detached or removed the ruler is susceptible of use in the ordinary way.

I am well aware that a combined ruler and blotter is not new; therefore do not claim such invention broadly.

I claim as my invention—

The combined ruler and blotter herein described, having the ruler A, attachable plate B, blotter D, and screws c, constructed and arranged in the manner set forth.

In testimony that I claim the above I have hereunto subscribed my name in the presence of two witnesses.

JAS. EMERY EATON.
